F. LOBNITZ,
ROPE GUIDING DEVICE FOR GROOVED OR RIBBED WINDING DRUMS.

APPLICATION FILED MAY 20, 1915.

UNITED STATES PATENT OFFICE.

FRED LOBNITZ, OF CROOKSTON, NEAR GLASGOW, SCOTLAND.

ROPE-GUIDING DEVICE FOR GROOVED OR RIBBED WINDING-DRUMS.

1,198,731.

Specification of Letters Patent. Patented Sept. 19, 1916.

Application filed May 20, 1915. Serial No. 29,439.

To all whom it may concern:

Be it known that I, FRED LOBNITZ, a subject of the King of Great Britain, residing at Crookston, near Glasgow, Scotland, have 5 invented certain new and useful Improvements in Rope-Guiding Devices for Grooved or Ribbed Winding-Drums, of which the following is a specification.

The subject of this invention is a device 10 for guiding ropes as they are being wound on and off a spirally grooved or ribbed winch or other winding drum.

The invention is specially designed for 15 use with double rope suspensions for rock cutting apparatus such as set forth in the specification of my prior Patent, No. 1,149,846, dated August 10th. 1915. The device prevents or tends to prevent the ropes of the suspension over-riding one another 20 when being coiled upon the winch drum.

The device forming the present invention is automatic in action and consists of a movable arm with guide means for the double 25 rope or ropes and a follower on the arm which works on the grooved or ribbed surface of the drum as it is rotated, thereby moving the arm and guide means to guide the ropes as they are being wound and un-wound.

30 The invention is illustrated in the accompanying drawings, in which,

Figure 1 represents a side view of the device as applied to the spirally grooved winch drum of a rock cutting apparatus in which the cutter has a double rope suspension. 35 Figs. 2 and 3 are respectively a plan and an end view corresponding to Fig. 1. Figs. 4, 5, and 6 are detail views of the follower.

Similar reference letters refer to similar 40 parts throughout the several views.

A is the winding drum for the double rope suspension B. The guide for the suspension B is constituted by an arm a pivotally supported at b, to the shear leg structure D of the rock cutting apparatus, and having, at 45 its end, a forked or slotted guide c, through which the ropes pass to the drum A. The guide c is caused to move laterally, as the ropes are being wound on and off the drum, 50 by a follower d. The follower d, as more clearly seen in Figs. 3, 4, and 5, is in the form of an oblong block curved at its under side d¹ to suit the periphery of the drum and is made with curvilinear ridges e which work 55 in the grooves E of the drum and, as the drum rotates, its grooves E cause the fol-

lower to move laterally and therefore move the guide c to which the follower is attached by means of a block f and screw g.

The guide c shown is formed of two metal 60 bars or pieces of angle iron h and h¹ secured at i to the arm a so as to leave a suitable space therebetween for the passage of the ropes. The ends of the pieces h and h¹ are connected by a bolt j and are maintained at 65 a suitable distance apart by a distance piece j¹ while the block f for the follower is secured between the pieces h and h¹ by bolts f¹.

It will now be apparent that I have invented a novel and useful rope guiding device, and while I have, in the present instance, shown and described a preferred embodiment thereof, it is to be understood that the same is susceptible to modification without departing from the spirit or scope of the 75 invention.

Having thus described my invention, what I claim and desire to secure by Letters Patent is:—

1. A rope guiding device for a grooved or 80 ribbed winding drum, consisting of a laterally movable arm, means on said arm forming a guide for the rope, and a follower secured to said means and having curvilinear ridges adapted to engage two of the grooves 85 of the drum.

2. A rope guiding device for a grooved or 90 ribbed winding drum, consisting of a laterally movable arm, means on said arm forming a guide for the rope, and an oblong follower removably secured to said means and having curvilinear ridges adapted to engage two of the grooves of the drum.

3. A rope guiding device for a grooved or 95 ribbed winding drum, consisting of a movable arm, means on said arm forming a guide for the rope, a block removably fitted in connection with said means, and a follower removably fitted in connection with said block said follower resting on and being automatically moved in a lateral direction 100 by the drum.

4. A rope guiding device for a grooved or 105 ribbed winding drum, consisting of a movable arm, means on said arm constituting a guide for the rope, and a follower in connection with the arm said follower being curved longitudinally and also having at its underside two curved and parallel ridges adapted to engage the irregularities of the 110 surface of the drum and be moved thereby.

5. A rope guiding device for a grooved or

ribbed winding drum, consisting of a pivotal arm, means on said arm constituting a guide for the rope, a block carried by said means, and a follower screwed to said block said follower being adapted to engage two of the grooves of the drum and be moved thereby in a lateral direction as the drum rotates.

6. A rope guiding device for a grooved or ribbed winding drum, consisting of a pivotal arm, a guide secured to the end thereof,

a block secured in said guide and a follower pivotally secured to said block and adapted to engage the grooves of the drum.

In testimony whereof I affix my signature in presence of two witnesses.

FRED LOBNITZ.
